Application October 16, 1936, Serial No. 105,952
In Germany August 31, 1935

2 Claims. (Cl. 101—351)

This invention appertains to a novel adjusting mechanism for printing presses, and more particular to adjusting mechanism for the ink fountain and rollers of printing presses utilizing aniline 5 inks.

Heretofore these presses were of an exceedingly expensive order due to the complicated mechanism employed for adjusting the ink fountain and associate rolls. It was thought necessary to 10 provide individual supports and adjustment on each side of the press for the ink and distributing rollers. Not only was the adjusting and supporting mechanism expensive, but adjustment was difficult, and undue wear occurred on the various 15 parts, rendering frequent and expensive replacements.

It is, therefore, one of the primary objects of my invention to provide an exceptionally simple, durable, and compact supporting and adjusting mechanism for the ink fountain and associate rollers, which can be manufactured and incorporated with an aniline or other printing 20 press at an exceedingly low cost.

Another salient object of my invention is to 25 provide a mechanism of the above character, which will be easy to adjust, and in which the various rollers will be held in proper line.

A further important object of my invention is to provide an adjusting mechanism, in which 30 wear will be reduced to a minimum, and in which wear can be compensated for by the accurate adjustment of the parts.

With these and other objects in view, the invention consists in the novel construction, arrangement and formation of parts, as will be hereinafter more specifically described, claimed, and illustrated in the accompanying drawing, in 35 which drawing:

Figure 1 is a fragmentary top plan view of a 40 press embodying my novel mechanism.

Figure 2 is a fragmentary side elevation of the same.

Figure 3 is a detailed vertical section taken on the line 3—3 of Figure 2, looking in the direction of the arrows.

Figure 4 is a similar section taken on the line 4—4 of Figure 2, looking in the direction of the arrows.

Referring to the drawing in detail, wherein 50 similar reference characters designate corresponding parts throughout the several views, the letter P generally indicates a printing press, which includes side frame plates 5. The press is of substantially the usual character, and, 55 therefore, only sufficient parts thereof have been

illustrated to show the operation of my novel mechanism. As illustrated, the frame plates 5 carry the upstanding arms 6, in which is journaled the shaft 7 for the impression cylinder 8. Normally, bearing against the impression cylinder 5 is the plate cylinder 9, and this cylinder in turn has normally bearing against the same the distributing roller 10. The distributing roller 10 is supplied with ink from the fountain 11 by means of the fountain roller 12.

These rollers are driven in some appropriate manner, which forms no part of the present invention.

My present invention appertains to a novel mechanism for supporting and adjusting the plate cylinder 9, the distributing roller 10, and the fountain roller 12. The frame plates 5 are provided with longitudinally extending slots 13, and the inner faces of the frame plates are planed smooth adjacent to the slots. If preferred the upper and lower walls of the slots 13 can be rabbeted, as at 14, for a purpose which will be later set forth.

Arranged against the polished inner faces of the frame plates 5 are the supporting slide plates 15. The inner face of the slide plates 15 have formed thereon longitudinally extending ribs 16, which are fitted within the slots 13, and these ribs have connected thereto by means of screws 17, or similar fastening elements, bearing plates 18, which engage the outer face of the frame plates 5. By this construction and arrangement of parts the slide plates 15 are firmly held against lateral shifting movement, and are prevented from twisting in any way. At the same time, the slide plates can be adjusted in the slots 13 toward and away from the impression cylinder 8.

In order to provide an additional support for the sliding plates, the same can be provided with longitudinal shoulders 19, which can fit snugly against the rabbets 14. The forward upper ends of the slide plates 15 carry suitable bearings 20 for the shaft 21 of the plate cylinder 9, and the plates 15 below the plate cylinder also carry suitable bearings for the shaft 22 of the fountain roller 12. The fountain 11 is also connected directly to the slide plates by the use of suitable supporting arms 23.

Rockably mounted upon the shaft 22 are levers 50 or links 24, the outer ends of which have pivotally connected thereto forwardly extending links 25. The links 25 carry suitable bearings for the shaft 26 of the distributing roller 10.

By adjusting the slide plates, all of the rollers 55

9, 10, and 12, and the fountain 11, can be moved toward and away from the impression cylinder.

Any appropriate mechanism can be employed for adjusting the slide plates 15, and in the present instance I have shown an adjusting screw 27 rotatably carried by a side frame plate 5. The screw 27 is held against longitudinal movement by a collar 28, and the operating handle 29 which is keyed or otherwise secured to the screw. The screw extends into an internally threaded bore 30 formed in a slide plate 15.

Obviously, when wear takes place on the slide plates 15, or on the frame plates 5, such wear can be taken up by suitable adjustment of the 15 set screws 17.

The distributing roller can be adjusted toward and away from the plate cylinder 9 by the use of an adjusting screw 31. This adjusting screw is rotatably carried by a sleeve 32 rockably mounted on a lever 24. Longitudinal movement of the screw 31 relative to its sleeve is prevented by a collar 33, and the operating handle 34 engaging the opposite ends of said sleeve. The lower end of the screw 31 is threaded into a stub 25 shaft 35 movably carried by a frame plate 5. By adjusting the screw 34 the levers 24 and 25 will be raised and lowered, and as the lever 24 swings about its axis 22, the roller 10 can be swung toward and away from the plate cylinder 9.

30 To bring about the adjustment of the distributing roller 10, relative to the fountain roller 12, an adjusting screw 36 is provided. The lower end of the screw is threaded into a suitable opening formed in a lip 37 carried by the lever 24. 35 This adjusting screw 36 is rotatably received within a sleeve 38 carried by or formed on the upper lever or link 25. The operating handle 39 for the screw 36 bears against the upper end of the sleeve 38, and an expansion coil spring 40 40 is placed around said screw and normally bears against the lip 37 and a shoulder on the sleeve 38. Obviously, by tightening or loosening the screw the distributing roller 10 can be raised or lowered.

From the foregoing description it can be seen that I have provided an exceptionally simple and durable mechanism for bringing about the accurate adjustment of an ink fountain and its associate rolls of a printing press.

Changes in details may be made without departing from the spirit or scope of my invention, but what I claim as new is:

1. In a printing press, a side frame plate, an impression cylinder rotatably carried by the frame plate, a slide plate, means for adjusting the slide plate toward and away from the impression cylinder, a plate cylinder rotatably supported by the slide plate and adapted to normally engage the impression cylinder, an ink fountain supported by the slide plate, a fountain roller rotatably mounted on the slide plate, a link rockably mounted on the supporting shaft for the fountain roller, a second link rockably carried by the outer end of the first link, a distributing roller rotatably carried by the second link, means for adjusting the position of the first mentioned link, and means for adjusting the position of the second link relative to the first mentioned link.

2. In a printing press, a side frame plate, an impression cylinder rotatably carried by the frame plate, a slide plate, means for adjusting the slide plate toward and away from the impression cylinder, a plate cylinder rotatably supported by the slide plate and adapted to normally engage the impression cylinder, an ink fountain supported by the slide plate, a fountain roller rotatably mounted on the slide plate, a distributing roller mounted between the fountain roller and plate cylinder and adapted to normally engage the fountain roller and plate cylinder, a pair of toggle links connecting the distributing roller with the slide plate, means for supporting the links of the toggle at their points of connection, means for raising and lowering the support, and means for adjusting one of said links independent of the support.

FRITZ STEINMETZ.
